UNITED STATES PATENT OFFICE.

MERLE JOHNSON, OF NEW YORK, N. Y., ASSIGNOR TO FRANK WALTON, OF NEW YORK, N. Y.

DESIGN FOR A STATUETTE.

Application filed December 27, 1922. Serial No. 4,729. Term of patent 3½ years.

To all whom it may concern:

Be it known that I, MERLE JOHNSON, a citizen of the United States, residing at 1440 Broadway, in the city, county, and State of New York, have invented a new and original Design for Statuette, of which the following is a specification, reference being had to the accompanying drawing, forming part thereof.

The drawing is a front view of a statuette embodying my invention.

I claim:

The ornamental design for a statuette as shown.

MERLE JOHNSON.
